US0D1110927S

(12) **United States Design Patent** (10) **Patent No.:** **US D1,110,927 S**
(45) **Date of Patent:** **** Feb. 3, 2026**

(54) **BICYCLE CARRIER**

(71) Applicant: **Yakima Products, Inc.**, Lake Oswego, OR (US)

(72) Inventor: **Jason Attfield Sagen**, Portland, OR (US)

(73) Assignee: **Yakima Products, Inc.**, Lake Oswego, OR (US)

(**) Term: **15 Years**

(21) Appl. No.: **29/942,939**

(22) Filed: **May 17, 2024**

(51) LOC (15) Cl. **12-16**

(52) U.S. Cl.

USPC **D12/408**

(58) **Field of Classification Search**

USPC D12/111, 406, 407, 408, 412, 414

CPC B60R 9/06; B60R 9/10; B60R 11/00

See application file for complete search history.

(57) **CLAIM**

The ornamental design for a bicycle carrier, as shown and described.

DESCRIPTION

FIG. 1 is a rear, top, and right side perspective view of a bicycle carrier showing the new design;

FIG. 2 is a front, bottom, and left side perspective view thereof;

FIG. 3 is a top plan view thereof;

FIG. 4 is a rear, top, and right side perspective view of a bicycle support of the bicycle carrier of FIG. 1;

FIG. 5 is a front, bottom, and left side perspective view thereof;

FIG. 6 is a rear elevation view thereof;

FIG. 7 is a front elevation view thereof;

FIG. 8 is a right side elevation view thereof;

FIG. 9 is a left side elevation view thereof;

FIG. 10 is a top plan view thereof; and,

FIG. 11 is a bottom plan view thereof.

The dashed lines in the drawing depict portions of the bicycle carrier that form no part of the claimed design.
